UNITED STATES PATENT OFFICE

123,905

DESIGN FOR A SNOW REMOVER

Walter E. Klauer, Dubuque, Iowa

Application February 21, 1940, Serial No. 90,427

Term of patent 14 years

To all whom it may concern:

Be it known that I, Walter E. Klauer, a citizen of the United States, residing at Dubuque, in the county of Dubuque and State of Iowa, have invented a new, original, and ornamental Design for a Snow Remover, of which the following is a specification, reference being made to the accompanying drawing, forming a part thereof.

Fig. 1 is a side elevation of a snow remover showing my new design;

Fig. 2 is a top plan view thereof;

Fig. 3 is a rear view thereof, and

Fig. 4 is a front view thereof.

I claim:

The ornamental design for a snow remover, substantially as shown.

WALTER E. KLAUER.
